UNITED STATES PATENT OFFICE

LOUIS B. WACKMAN, OF ST. LOUIS, MISSOURI

UNITARY CHIME FOR METALLIC CONTAINERS

Application filed February 2, 1932. Serial No. 590,426.

This invention relates to certain new and useful improvements in a unitary chime construction for metallic containers of the class of containers which are open topped or have a full opening when the cover is removed, the primary object of the invention being to provide a chime of a one piece construction.

Another object of the invention is in providing a chime which is made integral with or is formed in the top portion of the side wall of the container.

A further object of the invention is in providing a chime for a metallic container with an improved form of reinforcement.

A still further object of the invention is in providing a specific method of bending and forming the upper or top portion of a container wall into a chime with means on the chime for securing a cover thereto for the container.

Other and further objects will appear in the specification and be specifically pointed out in the appended claims, reference being had to the accompanying drawing, exemplifying the invention, and in which:

Figure 1 is a fragmentary sectional view of the upper portion of a metallic container showing this improved chime construction as forming a part of the container wall and a cover being secured in the chime.

Figures 2, 3, 4 and 5 are fragmentary sectional views illustrating the different steps presently used in forming this improved chime on the upper portion of a container wall.

Figure 6 is a fragmentary elevation of the meeting edges of the container wall forming a seam which is welded during construction of the container.

Figure 7 is a fragmentary sectional view illustrating the chime with an inlaid reinforcement.

In the accompanying drawing 1 designates the metallic side wall of the container which is made from a single sheet of material and

is joined on the longitudinal seam by welding in the manner as hereinafter described. Formed integral with the upper portion of the side wall 1 is this improved chime 2 having a gasket seat 3 and a holding or securing flange 4.

The seat 3 is for the reception of an annular gasket 5 on which the flange 6 of a cover 7 is seated, said cover having a depressed portion 8 which is engaged within the confines of the seat 3 and in sealing the cover to the container, a split locking ring 9 which is angular shaped in cross section is engaged so that the horizontal leg 10 thereof will be forced between the flange 6 of the cover 7 and the holding flange 4 of the chime 2, the wedging action of the leg 10 of the ring 9 causing the flange 6 of the cover to compress the gasket 5 on the seat 3.

A container having a chime of this character is primarily used for shipping semi-solid liquids, grease or dry materials.

The construction of this improved chime 2 is started while the material forming the side wall 1 is still in a flattened shape and while in this shape, the portion adjacent the edge of the material sheet which is to be used as the upper end of the container is outwardly bent and folded on itself as shown at 11 in Fig. 2. The next operation on the material sheet forming the side wall of the container is in rolling the sheet into a cylindrical shape and the contacting edges of the cylinder formed sheet are welded as shown at 12 and 13 in Fig. 6.

The welded cylinder is then operated on with adaptable corrugating rolls in engagement with the depending end 11a of the outwardly folded part 11 for forming an annular groove 14 in the wall 1 as shown in Fig. 3, this operation forcing the depending end or part 11a in the groove.

The cylindrical side wall 1 having the annular groove 14 is then further operated on to press the material of the groove or chan-

nel 14 together in a manner as shown in Fig. 4, thus providing the flat gasket seat 3 which is made relatively stiff and firm by reason of the reinforcement given thereto by the interposed portion 11a which has been tightly engaged between the material forming the groove 14 by the pressing operation on opposing sides of the groove.

The next operation is carried on to provide 10 the holding flange 4 which is done by operating on the upper portion 15 of the folded or lapped portion 11 of the side wall 1 for rolling the upper portion 15 into a right angular position as shown in Fig. 5, this operation 15 concluding the several operations described and shown with respect to Figs. 2, 3, 4 and 5 for providing this improved unitary chime of a U-shape in cross section comprising a gasket seat 3, a holding flange 4 and a 20 joining wall 16 for the seat 3 and flange 4.

With further regard to Fig. 6, the welding of the meeting edges of the side wall 1 of the container as shown at 12, is extended the vertical length of the side wall, over the folded 25 portion 11 and terminating at the upper edge of the folded portion. The welding 13 is carried on over the meeting edges on the inside surface of the wall 1 for an approximate distance as indicated between the dotted horizontal lines. This is occasioned by reason of 30 the fact that the welding shown at 12 will not penetrate sufficiently through the double thickness provided by the folded portion 11 and therefore the welding 13 for the distance 35 shown, is made for providing a sealed tight seam particularly through the gasket seat 3.

The disclosure of Fig. 7 is similar to that shown in Fig. 5, with the exception that a U-shaped reinforcing member 17 is interposed for providing a heavier and stronger 40 gasket seat 3a, holding flange 4a and a joining wall 16a, in the event that it is desired to provide a strong chime for relatively large containers.

45 Obviously constructional modifications of the device are possible without departing from the spirit of the present invention and therefore it is to be understood that it is not necessary to limit the invention by the terms 50 used in the foregoing description, excepting such as the state of the art may require.

What I claim is:—

1. A chime for a container comprising a metallic sheet having a part folded on one end 55 and rolled into a cylindrical body; the cylindrical body having a circumferential channel formed therein at the free end of said folded part, with the free end pressed into the channel; one side of the wall of said 60 channel forming a cover seat, and the folding edge of said folded part being angularly bent to form a locking flange above said seat.

2. A chime for a container comprising a metallic sheet having a part folded on one 65 end and rolled into a cylindrical body; the

cylindrical body having a circumferential channel formed therein at the free end of said folded part, with the free end pressed into the channel; one side of the wall of said channel forming a cover seat, and the folding edge of said folded part being angularly bent to form a locking flange above said seat; a cover for said seat, and a locking ring interposed between said flange and said cover.

3. A chime for a container comprising a metallic sheet having a part folded on one end, and a reinforcing layer of the depth of the folded part disposed within the fold of said part; the structure being rolled into a cylindrical body and having a circumferential channel formed therein at the free end of the folded part, with the free end of said folded part and said reinforcing layer pressed in the channel; one of the walls of the channel forming a cover seat, and the folding edge of said folded part being angularly bent to form a locking flange.

4. A container having a side wall comprising a metallic sheet bent upon itself to form an overlapped portion at one end and being rolled into a tubular body; said body having a circumferential channel formed on the outside thereof and having the free end of the overlapped portion pressed in the channel; said overlapped portion on its folding end being inwardly bent to form a ring-holding flange; and one of the walls of said channel forming a cover seat beneath said flange.

5. A container having a side wall comprising a metallic sheet bent upon itself to form an overlapped portion at one end and being rolled into a tubular body; said body having a circumferential channel formed on the outside thereof and having the free end of the overlapped portion pressed in the channel; said overlapped portion on its folding end being inwardly bent to form a ring-holding flange; one of the walls of said channel forming a cover seat beneath said flange; a cover for said seat; and a locking ring interposed between said flange and said cover.

6. A unitary chime for a container comprising a metallic sheet for providing a side wall for the container having a part folded on one end and rolled into a cylindrical body; the cylindrical body having a circumferential channel formed therein at the free end of said folded part, with the free end pressed into the channel; one side of the wall of said channel forming a cover seat, and the folding edge of said folded part being angularly bent to form a locking flange above said seat.

7. A unitary chime for a container comprising a metallic sheet bent to form an inwardly extended, upwardly and outwardly folded part, forming a channel; the sheet from the channel being upwardly and inwardly folded to form a locking flange; and the sheet from the flange being reversely

folded on the outside and terminating with its free end engaged in the channel.

8. A unitary chime for a container comprising a metallic sheet bent to form an inwardly extended, upwardly and outwardly folded part, forming a channel; the sheet from the channel being upwardly and inwardly folded to form a locking flange; and the sheet from the flange being reversely 10 folded on the outside and terminating with its free end engaged in the channel, and the side walls of the channel being pressed against said free end to form a cover gasket seat.

15 LOUIS B. WACKMAN.
